UNITED STATES PATENT OFFICE

HERMAN A. UNKE, OF CLEVELAND, OHIO

THREAD PROTECTOR

Application filed November 14, 1928. Serial No. 319,345.

This invention relates to devices for protecting the threads of pipes and other parts during handling and shipment.

It is one of the objects of this invention to provide an improved form of thread protector that can be produced at low cost, and which is adapted to be readily placed in position over the threads and not likely to become displaced while the pipe is being handled.

Another object of this invention is to provide a thread protector adapted to be screwed into position over the threads and having thread engaging means of an improved form.

Other objects and advantages of the invention will be apparent from the following description taken in connection with the accompanying drawings, of which:

Fig. 1 is an elevation of a pipe having a protector embodying my invention applied thereto, the protector and a portion of the pipe being shown in section;

Fig. 2 is a side elevation of the protector shown in Fig. 1, with a portion thereof broken away;

Fig. 3 is an elevation of the outer end of the protector;

Fig. 4 is an elevation of the inner end of the protector; and

Fig. 5 is a detail sectional view, on enlarged scale, of the lugs as shown in Fig. 1.

Referring now to the drawings in detail, Fig. 1 shows the end portion of a length of pipe 10 provided with the usual tapered threads 11, although the invention is in no way restricted to pipes or parts having tapered threads. To protect the threads 11, I arrange thereon a metal sleeve 12, which is preferably stamped from sheet metal and

provided at one end with an inturned flange 13 which frictionally engages the inner corner 14, of the end of the pipe 10, so as to assist in securing the protector in place. The inturned flange 13 also serves to reinforce the exposed end of the protector.

Additional reinforcement is provided by the flange 15 which extends radially inwardly from flange 13, and also by the rounded form of the exposed or outer end of the protector. At the

portion of the wall of the sleeve 12 is flared outwardly to form the skirt 16. The internal diameter of the skirt 16 is materially greater than the external diameter of the threaded portion so that the protector may be readily slipped over the end of the pipe, thus greatly facilitating the operation of arranging the protector on the pipe.

In forming the sleeve 12, I prefer to have the internal diameter of such size that the inner surface will not engage with the tops of the threads 11, thereby avoiding any mutilation of the threads in placing the protector thereon, or in removing it. For protectors for tapered threads, I prefer to make the sleeve 12 of slightly tapering form.

In order to secure the protector on the threads, and to prevent it from being knocked or jarred off, I provide lugs 17 on the inner periphery of sleeve 12 for engagement with the threads 11. These lugs are arranged in a plurality of circumferentially spaced axially extending rows, as shown in Figs. 2 and 4, so that the lugs of the different rows are in relatively helical arrangement conforming to the helix of the threads of the pipe. The lugs are preferably formed in a stamping press by means of dies, which displace slugs of metal radially inwardly from the wall of the sleeve by shearing force, and which swage these slugs to form the wedge shaped projections 17 on the inner periphery of sleeve 12, as is best shown in Figs. 1 and 2. The lugs of the different rows are spaced apart, in the axial direction, a distance which is a multiple of the distance between successive threads, and in this instance are shown spaced apart the distance of two threads.

In applying the protector to the pipe the lugs 17 engage and follow the threads 11 as the protector is rotated. The flange 13 is thereby brought to bear against the inner corner 14, of the end of the pipe 10, which causes lugs 17 to press against the sides, of the threads 11, that are remote from the end of the pipe. The cooperation of the lugs 17 and the flange 13 thus serves to prevent the protector from being removed from the pipe by straight axial movement.

While I have shown and described the pre-

ferred form of my invention, it will, of course, be understood that I do not regard my invention as limited to the particular embodiment disclosed, since various changes may be made therein without departing from the spirit of the invention and the scope of the appended claims.

Having thus described my invention, what I claim is:

1. A pipe thread protector comprising a continuous sleeve formed from sheet metal and having an outwardly flaring annular skirt at one end of said sleeve, and an inturned flange at the other end of said sleeve adapted to engage the inner corner of the end of a pipe, said sleeve having portions thereof pressed radially inwardly to form a plurality of substantially V-shaped solid lugs spaced axially and circumferentially of the sleeve in relatively helical arrangement for engagement with the threads when the protector is screwed on said pipe.
2. A pipe thread protector comprising a continuous metallic sleeve adapted to surround threads to be protected and provided with solid swaged lugs spaced axially and circumferentially on the inner periphery of said sleeve in relatively helical arrangement whereby the protector may be screwed on said threads, said lugs being formed from slugs of metal displaced radially inwardly from the wall of said sleeve.
3. A pipe thread protector comprising a continuous metallic sleeve adapted to surround threads to be protected and provided with solid substantially V-shaped swaged lugs spaced axially and circumferentially on the inner periphery of said sleeve in relatively helical arrangement whereby the protector may be screwed on said threads, said lugs being formed from slugs of metal displaced radially inwardly from the wall of said sleeve, and an inturned flange at one end of said sleeve adapted to engage the inner corner of the end of said pipe.
4. A pipe thread protector comprising a continuous metallic sleeve adapted to surround threads to be protected, and swaged substantially V-shaped solid projections on the inner periphery of said sleeve and spaced to engage the threads to be protected to retain the sleeve thereon.
5. A pipe thread protector comprising a continuous metallic sleeve adapted to surround threads to be protected, and swaged substantially V-shaped solid projections on the inner periphery of said sleeve and spaced to engage the threads to be protected to retain the sleeve thereon, and an inturned flange at one end of said sleeve adapted to frictionally engage the end of said pipe.

In testimony whereof, I hereunto affix my signature.

HERMAN A. UNKE.
